[57] **CLAIM**

The ornamental design for an emergency water retaining wall section, as shown and described.

DESCRIPTION

FIG. 1 is a perspective view of the emergency water retaining wall section showing my new design;

FIG. 2 is a left end elevational view thereof, the right end elevational view being a mirror image of the view shown in this Figure;

FIG. 3 is a front elevational view thereof, the rear elevational view being a mirror image of the view shown in this Figure; and,

FIG. 4 is a top plan elevational view thereof, the bottom plan view being a mirror image of the view shown in this Figure.
